ELECTRICAL METER

Elbert K. Mackenzie, North Wales, Pa., assignor to Electro-Mechanical Instrument Co., Inc., Perkasie, Pa.

Filed Aug. 2, 1971, Ser. No. 168,536

Term of patent 7 years

Int. Cl. D10—04

U.S. Cl. D52—6 R

FIG. 1 is a front perspective view of a volt meter showing my new design;

FIG. 2 is a right side elevational view thereof, the left side being a mirror image thereto;

FIG. 3 is a rear elevational view thereof, having the base folded down in a wall mountable position;

FIG. 4 is a right side elevational view of FIG. 3.

I claim:

The ornamental design for an electrical meter, substantially as shown and described.
